[57] **CLAIM**

The ornamental design for a press pin remover, as shown and described.

DESCRIPTION

FIG. 1 is a front perspective view of a press pin remover, showing my new design;

FIG. 2 is a partially unassembled rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken line portion of FIG. 1 depicting a press pin being removed from a latch is for illustrative purposes only and form no part of the claimed design.
